UNITED STATES PATENT OFFICE

165,651

CRIBBAGE BOARD

William C. Horn, Orange, N. J.

Application April 28, 1950, Serial No. 9,539

Term of patent 14 years

(Cl. D34—5)

To all whom it may concern:

Be it known that I, William C. Horn, a citizen of the United States of America, residing in Orange, in the county of Essex and State of New Jersey, have invented a new, original, and ornamental Design for a Cribbage Board, of which the following is a specification, reference being had to the accompanying drawings forming part thereof, wherein:

Fig. 2 is a side elevation thereof.

The dominant features of my new design are shown in solid lines in the drawing.

The two central longitudinal narrow strips are lined to indicate contrasting color.

I claim:

The ornamental design for a cribbage board, as shown and described.

WILLIAM C. HORN.
